BURNER

Rolland C. Sabins, Columbus, Ohio

Application September 4, 1941, Serial No. 409,476

4 Claims. (Cl. 158—91)

This invention relates to a new and improved burner and more particularly to a pot type burner of the character used in stoves or heaters burning liquid hydrocarbons.

Burners of this character vaporize or gasify the liquid fuel and burn it as a gas or vapor. The burner is fed with fuel which spreads into a thin layer or film upon the bottom of the pot. This layer or film is heated by radiant heat from the flame which is spaced upwardly from the liquid and also by means of heat conducted through the walls of the vessel. Air is admitted into the pot burner through small openings in the lateral wall. These openings are located at varying heights upon the wall. The lower openings admit primary air which causes a preliminary or partial combustion of the gases and vapors adjacent the oil film upon the bottom of the pot. This primary combustion heats the film to cause the vaporization and gasification necessary to support the combustion. It also heats gases and vapors passing through or adjacent the lower or primary flame so that the gases and vapors are further broken down. The sensible heat imparted to the gases and vapors as well as their breaking down provides a hot upper flame when these gases meet the secondary air coming in through upper series of openings in the pot walls. When properly designed, the combustion is complete and the products of combustion are free from soot or unburned gases.

The efficient design of a burner adapted to operate upon a given rate of fuel flow is relatively simple. In commercial practice, however, it is necessary to provide a burner capable of operating over a relatively wide range of heat production and consequently with a similarly wide range of fuel supply. This is especially true when the burners are used in space heaters. At times it is desired to operate the burner with a low pilot flame and a minimum fuel consumption. At other times the maximum heat output is desired. The requirements may suddenly change from the minimum to the maximum, as, for example, when the heater is thermostatically controlled to maintain the heated space or rooms to a given temperature.

The operation of such burners is normally controlled by means of adjustable or variable fuel metering valves in connection with a constant level valve giving a fuel flow under a constant head or pressure. One form of construction designed for the purpose of improving combustion over a wide range of valve settings comprises a ring located in the lower portion of the burner

and extending inwardly from the walls. Primary air openings are located below such rings and secondary air openings above the rings. In some constructions additional secondary air may be said to enter above the ring. While such a ring may cause efficient operation at low or intermediate fuel settings, it lowers the efficiency at high fuel settings. This is for the reason that the ring shields a substantial portion of the burner bottom from the radiant or reflected energy of the flame. Further, such rings are of thin metal and usually are placed loosely in the burner, resting on pins or other spaced supports. Consequently, heat absorbed by the ring is not adequately transferred to the pot wall and bottom by conduction. Thus the heat is not transmitted where it is needed and in addition there is the tendency for the ring to get so hot that it distorts and sags out of its proper position. In extreme cases the ring may sag into the streams of air coming from the primary air openings below the ring and have holes burned through it. To reduce these objectionable results it is necessary to make the rings of more expensive, heat resistant steel.

It is an object of the present invention to provide a new and improved pot type burner operating efficiently throughout a wide range of fuel consumption.

It is also an object to provide a burner having baffle means exposing portions of the base of the burner adjacent the wall to heat from a flame in the upper portion of the burner.

It is an additional object to provide baffle means connected to the burner walls in such manner as to facilitate heat transfer thereto.

It is another object to provide a burner construction having no air openings extending through the pot walls below the baffle means.

It is also an object to provide circumferentially spaced baffle means and air openings adapted to direct air upwardly and downwardly adjacent the spaces between the baffle means.

It is a further object to provide a burner having a central raised portion in the base to make the flame more stable in location and increase the efficiency of the combustion.

It is an additional object to provide baffle means which is rigid in construction and adapted for manufacture from inexpensive materials.

It is another object to provide a burner which is simple in design and operation and adapted for commercial production and use.

Other and further objects will appear as the 55 description proceeds.

I have shown a preferred embodiment of my invention in the accompanying drawings, in which—

Figure 1 is a plan view of a pot type burner constructed according to the present invention;

Figure 2 is a vertical section through the burner of Figure 1;

Figure 3 is a fragmentary perspective, showing a baffle member and associated upwardly directed opening;

Figure 4 is similar to Figure 3 showing a downwardly directed opening;

Figure 5 is a fragmentary plan view, partly in section, showing the method of mounting the baffles;

Figure 6 is a perspective view of a baffle as seen from the rear; and

Figure 7 is a fragmentary section showing the fuel inlet to the bottom of the burner.

Referring first to Figures 1 and 2, the burner comprises a substantially cylindrical wall portion 11 having a slightly depressed bottom portion 12. The bottom portion 12 is provided with a centrally located raised section 13, the center portion 14 of which may be adjusted vertically. This portion 13 is shown in the drawings as a separate member welded into the bottom 12. The upper portion of the pot wall flares outwardly for a short distance, this outwardly flared portion being provided with a plurality of air inlet openings 15, and the wall has a cylindrical portion 16 above these openings. A plurality of series 17, 18 and 19 of openings for introduction of air into the burner are provided at spaced points upon the vertical wall 11.

The ring 20, best shown in Figure 5, is provided in the lower portion of the burner, this ring having portions 21 which are secured to the inner face of the burner wall by spot-welding or by any other desired means. Intermediate portions 22 of the ring extend inwardly and are spaced from the wall 11. These portions 22 are adapted to receive the baffle members 23 and to retain them in place. As best shown in Figure 6, each baffle member 23 is provided with a downwardly extending portion 24 which is adapted to fit in behind a ring portion 22. Each member 23 is also provided with lateral wall portions 25 and 26 which extend rearwardly and engage the lateral shoulders 27 and 28 of the ring portion 22, as best shown in Figure 5. The edges of the walls 25 and 26 engage the face of the intermediate ring portions 21. The baffle members 23 are thus rigidly supported and have substantial surfaces in contact with the ring 21 so as to transmit heat to that ring and through the ring to the pot wall 11.

As shown in Figures 1 and 5, the inner ends of the members 23 are closely adjacent each other, while the outer ends secured to the wall are spaced apart. There are thus provided a plurality of triangular spaces, the apices of which intersect the central circular opening formed by the inner edges of the members 23. These openings permit transfer of gases and vapors from the lower portion of the burner to the upper portion and they also permit radiant heat to pass downwardly from the upper portion of the burner to the bottom of the burner.

As shown in Figures 3 and 4, the lowermost row of air openings is located immediately above the ring 21 and comprises openings 31, shown in Figure 3, which incline upwardly and direct the entering stream of air upwardly, and also the openings 32, shown in Figure 4, which are in-

clined downwardly and direct the entering stream of air downwardly. These upwardly and downwardly directed openings are placed alternately in the series. The pot is provided adjacent its bottom with a fuel inlet opening 33, as shown in Figure 7, and also as shown in Figure 7 may be made without the central raised portion 13. The upper portion of the burner is provided with the circular flange 34 by which the burner is usually supported upon a partition or flange formed integrally with the combustion chamber or housing with which the burner is associated in use.

The baffle members 23 comprise die-formed metal sections which may be cheaply formed from ordinary black iron. Since the sections are rigid in design, due to their positive support and their lateral walls 25 and 26, they will not sag under heat and due to their location will not get in the line of flow from any of the air inlet openings. It is thus unnecessary to form the sections of more expensive heat resisting alloy steels. Further, should any section become damaged, it may be replaced without the necessity of replacing other adjacent sections. These baffle sections are so positioned that the entire wall below them is imperforate and no primary air is admitted below their level.

The upwardly directed openings 31 and downwardly directed openings 32 are located opposite the triangular spaces intermediate the baffles and are alternately placed. Thus air is directed downwardly upon one side of each baffle and upwardly upon the opposite side. The downwardly directed air streams pass downwardly between the sections and supply primary combustion supporting air in the lower zone below the baffles. These streams also provide means for purging the heavy oil vapors in the lower zone and causing them to flow inwardly and upwardly in the center of the burner where they will mix with the combustion supporting air coming in through the upper series of openings. The intermediate upwardly directed air streams flowing through openings 31 also tend to cause upward flows at intermediate portions of the periphery of the burner so that the vapors and gases are kept moving and uniformly mixed and burned. The gases are carried upwardly and reach their final combustion stage by mixing with the secondary air coming in from the upper rows of openings.

Due to their wide contact with the ring 21 and its intimate contact with the burner walls, heat from the burner sections is carried to the burner walls and bottom, which results in the thorough heating of the liquid fuel on the bottom. This additional heat gives the burner the ability to burn efficiently a very low flame, the heat aiding in generation of vapors in the bottom thereof. The burner also is very efficient in high fire operation and reaches a proper operation at high fire setting much more rapidly than a conventional type of burner with a flat pilot ring or baffle. The fact that the baffle sections 23 are spaced apart allows the reflected and radiant energy from the flame above the baffle to pass directly through the baffle and raise the temperature of the burner bottom and of the gases and vapors between the bottom and the baffle. An ordinary flat type of ring baffle prevents the passage of this radiant heat. Also, the larger volume of gases being generated on the bottom at medium and high fire are caused to flow upwardly between the segments or baffle sections 23 by means

of the upwardly directed air jets through openings 31, which causes them to mix more thoroughly and more rapidly than with the conventional type of flat pilot or baffle ring, which forces all the gases to pass out through the annular opening in the center of the ring.

The raised portion 13 with its adjustable section 14 in the center of the bottom of the burner, has been found in actual practice to locate the center of the flame and to cause the flame to burn more steadily than where this element is not used. It also serves to heat the gases to a higher degree of temperature and to cause the flame to burn with a bluer tinge. Without this raised portion, and particularly with the usual type of ring baffle, there is a tendency for the flame at low levels to float around the bottom area with a continuously moving flame center. It is not necessary that the raised portion 13 have an adjustable element, as it may be made as a portion of the bottom 12 and when properly proportioned to the size of pot and the character of the baffle, will function efficiently. As shown in Figure 7, the raised portion may be eliminated entirely and the remainder of the burner construction, including the specific form of baffle, will function to have the advantages which have been set forth herein.

The forms of construction shown are to be understood to be illustrative, as portions and relationships of the parts may be modified to meet varying conditions and requirements, and I con-

template such variations as come within the spirit or scope of the appended claims.

What is claimed is:

1. In a pot type burner, a circumferentially extending ring secured to the inner wall of the burner at an intermediate point thereon, portions of the ring being spaced from the wall, and baffle members having downwardly extending portions fitted in spaces between the ring and pot wall.
2. In a pot type burner, a circumferentially extending ring secured to the inner wall of the burner at an intermediate point thereon, portions of the ring being spaced from the wall, and baffle members having downwardly extending portions fitted in spaces between the ring and pot wall, said baffle members having downwardly directed flanges engaging the inner face of the ring.
3. In a pot type burner, a plurality of baffles of limited circumferential extent secured to the pot wall and extending inwardly therefrom, the baffles having spaces therebetween in plan view, the pot wall having openings therein adjacent said spaces.
4. In a pot type burner, a plurality of baffles of limited circumferential extent secured to the pot wall and extending inwardly therefrom, the baffles having spaces therebetween in plan view, and having additional openings therein above the baffles, the portion of the pot wall below the baffles being imperforate.
